MAGNETIC TOY FIGURE

George Lerner, Freeport, and Julius Ellman, Brooklyn,
N.Y., assignors to Hasbro Industries, Inc., Pawtucket,
R.I.

Filed May 15, 1970, Ser. No. 23,004

Term of patent 14 years

Int. Cl. D21—02

U.S. Cl. D34—4

FIG. 7

FIG. 6

FIG. 1 is a perspective view of the magnetic toy figure showing our new design;

FIG. 2 is a top plan view thereof;

FIG. 3 is a bottom plan view thereof;

FIG. 4 is a right side view thereof, the side not shown being a mirror image of the side shown;

FIG. 5 is a rear elevational view thereof;

FIG. 6 is a perspective view of the magnetic toy figure shown in FIG. 1, but with alternate eyes, ears, nose, mouth and hat; and

FIG. 7 is a perspective view similar to that of FIGS. 1 and 6 but with further alternate eyes, ears, nose, mouth and hat.

We claim:

The ornamental design for a magnetic toy figure, substantially as shown and described.
